MODULAR LAMP

Denis P. Desrochers, 1023 Charon Beach,
Belle River, Ontario, Canada

Filed May 21, 1973, Ser. No. 362,008

Term of patent 14 years

Int. Cl. D26—05

U.S. CL. D48—20 A

FIG. 1 is a side elevational view of a modular lamp showing my new design.

FIG. 2 is a front elevational view thereof with the pivoted rod in an alternate position.

The pedestal is flat, circular and unornamented.

I claim:

The ornamental design of a modular lamp, as shown.
